MACARONI AND MEANS FOR PRODUCING
THE SAMEGuido Tanzi, Brooklyn, N. Y., assignor to V. La
Rosa & Sons, Inc., Brooklyn, N. Y., a corpora-
tion of New York

Application July 10, 1933, Serial No. 679,667

7 Claims. (Cl. 107—14)

This invention relates in general to the fabrication of articles by the extrusion of various plastic materials through dies, and is concerned more particularly with improvements in the form and the means of production of macaroni in a now-preferred embodiment.

An object of the invention is to produce a novel kind of macaroni (or noodle) which may be embodied in various specific forms having certain characteristics in common which are disclosed in the present application and are set forth in the generic claims thereto appended.

This novel generic characteristic comprises a formation in which each article, say of macaroni, or a noodle, is of hollow structure and presents a periphery having a plurality of spaced annular constrictions or furrows which may desirably lie in planes respectively parallel to each other, and normal to a selected axis of the shell, (as the latter will be hereinafter designated, for the sake of brevity), as for example the major axis of the shell when the latter is longer in one dimension than in another although it is obvious that shapes of shells closely approaching a spherical contour, also oblate spheroids, and more irregular shapes, may embody the generic furrowed characteristic above mentioned.

Another object of the invention is to produce a shell-form article of plastic material comprising an integral, broad, thin strip of plastic material curved around an axis of the shell so as to bring its ends into at least approximate registry or abutting relation with each other, substantially in a plane passing through the selected axis of the shell, so that the general effect may be that of a closed shell, although in the case of such a shell-form macaroni or noodle it is preferred to leave an opening sufficient to afford access of cooking fluid to the interior of the shell, so that the dough may be thoroughly and uniformly cooked throughout its thickness, and for the same reason the strip of material will preferably be of substantially uniform thickness throughout its breadth, whatever may be the final shape of the completed product.

A cognate object of the invention is to provide novel means for extruding continuously a strip of plastic material, such as macaroni dough, in such a manner that the extruded material will, by virtue of the very manner of extrusion form itself into successive shells of the desired shape, and also to provide appropriate means for severing each of these shell-forms from the parent strip immediately upon its completion, without interfering with the continuity of the process of ex-

trusion, nor with the perfect formation of the next shell to be extruded.

Still another object of the invention is to provide auxiliary means adapted to receive the extruded shells after they have been parted from the parent strip, and to act automatically upon the shells in such a manner as to aid the above described tendency of the extruded material to assume the desired closed shell-form, the novel means herein disclosed being designed to receive a multiplicity of such articles upon their approximately simultaneous discharge from the extrusion orifices of a series of die-plugs in a die-plate through which the plastic material is pressed according to the conventional usage.

Other features of the invention will become apparent from the appended drawing and description.

In the drawing,

Fig. 1 is a view in side elevation of a die-plate, of conventional form, partly broken away to show in section one of the recesses adapted to seat a die-plug of the type designed to form the novel product hereinafter disclosed, with one of the die-plugs seated therein.

Fig. 2 is a bottom plan view, on a larger scale, of one form of die-plug adapted to extrude a shell-form article according to the invention, such as a macaroni or noodle.

Fig. 3 is a view in vertical section on the line 3—3 of Fig. 2.

Fig. 4 is a top plan view of the die-plug shown in Figs. 2 and 3.

Fig. 5 is a view in side elevation of the novel shell-form article constituting a now-preferred form of macaroni or noodle embodying the invention.

Fig. 6 is a similar view of another, modified species of shell-form product embodying the invention.

Fig. 7 is a bottom-plan view of a die-plug adapted to extrude the specific form of product shown in Fig. 6.

Fig. 8 is a top-plan view of the die-plug shown in Fig. 7.

Fig. 9 is a fragmental, detail view in bottom-plan of a die-plate, such as that shown in Fig. 1, with several die-plugs fitted therein of the type illustrated in Figs. 2—4 inclusive, and illustrating also means for severing the shell-form articles successively from their parent strips upon complete extrusion of each such article, one of which is shown, ready for severance.

Fig. 10 is a view in vertical section, upon a reduced scale, of a press, with a die-plate fitted

with die-plugs, in its operative position, and in combination therewith an auxiliary means for receiving from the die-plugs the extruded and severed shell-form articles, and for completing 5 the closure of said articles.

In pursuance of that aim of the invention which is to produce various specific shapes of articles having the novel generic characteristic of a hollow shell formed with peripheral furrows or constrictions in spaced, substantially parallel relation, I have devised, among others, and have illustrated herein, two such species, shown respectively in Fig. 5 and in Fig. 6, each comprising a broad strip S of material curved around 10 in such a manner as to bring its ends s into approximately closed, abutting relation, and the hollow shells thus constituted are respectively formed with constrictions or furrows s', at spaced intervals along the major axis of each of the shells, the latter being of greater length than 15 thickness, in the illustrative species shown.

As already indicated in the opening statement of the aims of the present invention, a shell-form article of plastic material, comprising a single 20 strip of material extruded with the furrowed characteristic disclosed, is in itself novel and is so claimed generically, whether made by the exact practice of the novel method herein set forth and claimed, or by the particular apparatus 25 or means also disclosed and claimed, or by other suitable means and/or methods, and the specific shell shapes shown in Figs. 5 and 6 are merely illustrative of the generic invention, which may be embodied in many other shapes.

As to the now-preferred method herein disclosed for making shell-form articles of this novel generic form, I conceive it to be broadly novel to extrude a wide strip of plastic material continuously in such a manner as to cause it to curl about 30 a transverse axis into a hollow, substantially closed shell-form, and to sever successively the individual shells thus formed from the parent strip, this procedure being better understood from the following description of one suitable means 35 for accomplishing the desired result.

In the now-preferred embodiment of such means selected for illustration, and referring to Figs. 1, 2, 3, 4, 9, and 10 more particularly, the part designated by the reference character 11 is a 40 die-plate of conventional form, having a series of recesses 12, of which one is shown in vertical section, and another in dotted lines, adapted to serve as seats for die-plugs by which the invention may be carried into effect, this die-plate with its equipment of die-plugs 13 being shown in Fig. 10 as 45 mounted in a die-press 14 of conventional form, to which reference will be made hereinafter.

Each die-plug 13 may desirably comprise a hollow metal cup-like member having a base 15 provided with an extrusion orifice 16 the walls of which are of wavy contour and so are adapted to extrude a broad, relatively thin strip of plastic material, which, in the case of macaroni dough for example, is preferably of substantially uniform thickness, so that it will be cooked uniformly when immersed in a suitable cooking fluid at the proper temperature, after completion of the product.

In the form shown in Figs. 2, 3, and 4, the general contour of the orifice 16 is arcuate, from end to end, in order to produce a hollow shell having a medial portion of larger diameter, tapering toward the major axis at each end, as clearly shown in Fig. 5, and in pursuance of the invention, the die-plug is of suitable construction to permit

more rapid feeding of the plastic material at this medial region than at the ends of the orifice, for which purpose I have shown the material of the base 15 as relieved centrally to form a concavity or pit 17, which in the instance shown is in the shape of a rather flat cone, as that contour has been found by experiment a suitable shape to produce the intended result. Such a contour is illustrative rather than essential, however. This concavity 17 reduces the thickness of the base of the die-plug and accordingly reduces the resistance which the extrusion orifice offers to the flowing material therefore permitting more rapid feeding at the region of the concavity.

I have also provided holes or enlargements 18 of the extrusion orifice at regions where it is desirable to permit more rapid extrusion of the component material, and it is to be observed that these enlargements coincide with the ridges s² at each side of the furrows s', toward the respective ends of the product.

In operation, the plastic material, such as macaroni dough, is placed in the press 14, and the plunger 19 is forced down, causing the dough to be extruded through the orifices 16 in the die-plugs 13, each die-plug discharging a portion of strip S which, without guiding means, curls upon itself as indicated at 20 in Fig. 9, to form a shell product or article of the shape shown in Fig. 5, and when the free end of the extruded strip 105 reaches approximately the relative position indicated at s in Fig. 5, it is severed from the parent strip by suitable means, the product having been completed.

Any suitable means may be provided to accomplish such severance, and as one such suitable construction I have shown in Fig. 9 a knife 21, mounted pivotally on the central bottom face of the die-plate 11, and driven by suitable means (not shown) so as to sweep around and progressively cut off the strips as the shells are extruded from the die-plugs 13 successively.

In pursuance of another aim of the invention, I may provide auxiliary means to accumulate the completed shells and adapted to act simultaneously upon considerable numbers thereof to aid in closing the ends s of each shell together, for which purpose I have devised, and illustrated in Fig. 10, an inclined screen 23, mounted on rock-arms 24, driven reciprocatingly by links 25, 26 connected to a crank-pin 27 on a shaft 28, operated by a suitable source of power (not shown).

As the shells are parted from their parent strips by the knife 21 they fall upon the shaping screen 23 and gradually roll down the latter, the reciprocating action tending to roll each shell backward and forward slightly, so that the shells are closed up more or less accurately to the position shown in Fig. 5.

This, however, is not an essential step in the operation of producing such shell-forms, and ordinarily the action of the die-plugs, by virtue of their extrusion more freely of plastic material at the side of the orifice which forms the high parts of the ridges between the furrows, as already described, is sufficient to cause curling of the strip around an axis transversely to its length to an extent adequate to deform the strip into the desired shell-form which it is the aim of the invention to produce.

As already indicated, various modifications of the shell-form produced in pursuance of the invention above disclosed may be made without departing from the spirit thereof, and one such modification in shape is shown in Fig. 6; with

suitably modified means for its manufacture, as illustrated in Figs. 7 and 8.

Fig. 7 is a bottom plan view, similar to Fig. 2 but shows a die-plug 29 having a base 30 in which is provided a wavy extrusion orifice 31, extending diametrically across the base, and adapted to extrude a shell of the elongated cylindrical shape shown in Fig. 6, with peripheral furrows or annular constrictions as shown at s'.

10 The curling of the strip-end as the plastic material is extruded through this die is caused by the provision of enlargements or holes 32, in the upper face of the base 30, one such enlargement of the extrusion orifice being provided at the 15 crest of each wavy portion of the orifice along one side of the latter, these enlargements so diminishing the thickness of the walls of the orifice at their respective regions as to diminish correspondingly the resistance to flow of the material 20 at those regions, so that the material flows there more freely than at the crests 33 on the opposite side of the orifice.

Therefore the emerging free end of the extruded strip tends to curl around an axis transversely to its length, from the crests 32 around and toward the crests 33, and when the shell-form edges reach a relative position approximately that shown in Fig. 6, the completed product is cut off by suitable means, such for example as a swinging knife of the type shown in Fig. 9, and already described.

The corrugated shell-forms of product illustrated herein, and others of like fabrication, constitute novel and attractive species of macaroni or noodles, and they can be readily and thoroughly cooked and prepared for consumption, tending to retain within their central cavities the gravies or juices with which they are prepared.

40 In practice, the adjacent free edges of the shell may, and frequently do, overlap each other more or less, causing the shell to assume a somewhat spiral form in cross-section, as can be well understood without illustration.

45 I claim:

1. An extrusion means for producing macaroni in shell-form, said means comprising a die-member having an open feeding end and a restricted extrusion end provided with an elongated extrusion orifice in the form of a slot of sensibly uniform width throughout its length, adapted to extrude a broad strip of dough, of substantially uniform thickness throughout its area, said orifice being of wavy contour, to impart to said extruded strip a series of furrows or corrugations extending lengthwise of said strip, said orifice being further characterized by having a posterior concave enlargement thereof adjacent to the middle region of said orifice, said medial enlargement being of sensibly flat conical contour, with its apex at the center of said orifice and subsidiary enlargements located at the crests of certain of the wave-producing regions of said orifice other than the apex of said conical enlargement.

60 2. An extrusion means for producing macaroni in shell-form, said means comprising a die-member having an open feeding end and a restricted extrusion end provided with an elongated extrusion orifice adapted to extrude a broad strip of dough of substantially uniform thickness throughout its area, said orifice being of wavy contour, to impart to said extruded strip a series of furrows or corrugations extending lengthwise of said strip, said orifice being further char-

acterized by having a plurality of individually localized posterior enlargements thereof located at the crests of certain of the wave-producing regions, to cause relatively rapid feeding of material at the regions of said enlargements, and thereby to produce hollow spheroidal enlargements in certain of said corrugations.

5 3. Apparatus for producing shell-form nuggets of macaroni or similar plastic materials, comprising means to extrude a (multiplicity of) broad strip (s) of plastic material such as macaroni dough with a curling bias around an axis extending transversely of the length of the extruded strip, means to sever successive portions from the parent strip as the free end thereof approaches the body of the strip upon completion of each nugget, and means to receive the severed nuggets and roll them to and fro upon their peripheries to close the ends of said shell together.

10 4. The method of producing shell-form nuggets of macaroni which comprises the step of extruding a broad strip of macaroni dough in such a manner as to create therein an inherent tension with a curling bias around an axis transversely to the length of said strip and severing said strip successively at stages when the free extruded end approaches the body of the extruded strip and permitting the inherent curling action to continue in each of the severed articles until the severed ends are substantially in juxtaposition with each other, and the further step of rolling the shell-form nuggets to and fro upon their peripheries to complete their closure.

15 5. In a molding machine adapted for extruding plastic material, a plate having a plurality of passages extending inwardly from one side partly through the plate, said passages arranged in a row, said plate having a slot therein extending back from the opposite side of the plate to the passages, said slot extending back between the passages to substantially greater distance than the distance from said opposite face to the passages, the greater extension back of the slot between the passages effecting the coalescence of the material before its extrusion from the plate, and said slot being formed in a series of jointed arcs with their convexities in substantially the same direction, certain of the convexities being in communication with certain of the passages, said passages and slot effecting the curving back 105 to the plate of the extruded material.

110 6. In a molding machine adapted for extruding plastic material, a plate having a plurality of passages extending inwardly from one side partly through the plate, said passages arranged in a row, at least one of said passages being of larger cross-sectional area than others, said plate having a slot therein, opposite said passages, extending back from the opposite side of the plate to the passages, and said slot being formed in a series of jointed arcs with their convexities in substantially the same direction, certain of the convexities being in communication with certain of the passages, the material extruded from the slot curving back toward the plate and forming a shell-like hollow body having a relatively large diameter at the region of extrusion from said passage or passages of larger cross-sectional area.

115 7. In a molding machine adapted for extruding plastic material, a plate having a plurality of passages extending inwardly from one side partly through the plate, said passages being of substantially circular cross-section and arranged in a row, the bottom of each passage being substan-

entially cone-shaped with the apex pointing toward the opposite side of the plate, said plate having a slot therein extending back from the opposite side of the plate to the passages, said slot being formed in a series of jointed arcs with their convexity in substantially the same direction, an arc for each passage, and the junction of ad-

jacent arcs coming between their corresponding passages, said passages and slot causing the material extruded therefrom to be formed in a series of rounded transverse ridges curving longitudinally back toward the plate.
